UNITED STATES PATENT OFFICE.

HAYDN WEBSTER BARROWS, OF MORRIS PARK, NEW YORK.

DESIGN FOR AN ELECTRIC LAMP.

Application filed November 17, 1921. Serial No. 515,958. Term of patent 3½ years.

To all whom it may concern:

Be it known that I, HAYDN WEBSTER BARROWS, a citizen of the United States, residing at Morris Park, in the county of Queens and State of New York, have invented a new, original, and ornamental Design for Electric Lamps, of which the following is a specification, reference being had to the accompanying drawing, forming part thereof.

The drawing gives a perspective view of an electric lamp, showing my new design.

I claim:—

The ornamental design for an electric lamp, as shown.

In witness whereof, I hereunto subscribe my name this 15th day of November, 1921.

HAYDN WEBSTER BARROWS.
